UNITED STATES PATENT OFFICE.

CHARLES HENRY HIGGINS, OF CINCINNATI, OHIO.

OIL-HEATED OVEN.

SPECIFICATION forming part of Letters Patent No. 716,230, dated December 16, 1902.

Application filed March 31, 1902. Serial No. 100,712. (No model.)

To all whom it may concern:

Be it known that I, CHARLES HENRY HIGGINS, a citizen of the United States of America, and a resident of 636 East Sixth street, in the city of Cincinnati, in the county of Hamilton, and State of Ohio, (post-office address 1209 Sycamore street, in the city of Cincinnati,) have invented an Improvement in Oil-Heated Ovens; and I do hereby declare that the following is a full and exact description thereof, reference being had to the accompanying drawings, making part of this specification.

My invention relates to oil-heated ovens; and it has for its object the improvement in the construction of such devices, whereby they are simplified and rendered more efficient.

The novelty of my invention consists in the combination and subcombination of the parts, as will be hereinafter set forth, and specifically pointed out in the claim.

In the accompanying drawings, Figure 1 is a plan view of my oven. Fig. 2 is a side elevation. Fig. 3 is a section on line 3 3 of Fig. 2. Fig. 4 is a section on line 4 4 of Fig. 1. Fig. 5 is a section on line 5 5 of Fig. 1. Fig. 6 is a section on line 6 6 of Fig. 1.

Similar letters of reference indicate like parts throughout the several drawings.

My oil-heated oven consists of a suitable outside casing A, supplied with oil-burners B, located as shown in Figs. 4, 5, and 6. The oven is constructed so as to be in the form of a series of shelves C C C C, attached to a front casting E, mounted on rollers F, the inner portion sliding in ways G. This construction permits the removing of the shelves composing the oven out, so that the contents can be readily handled or inspected. I have provided also glass windows H for my

oven, so that without opening the oven a view can be had of the interior of the oven at any time. To facilitate the view of the interior of the oven, I have provided a light I, which is located opposite one of the windows H, so that in looking into the oven from the opposite side from which the light is on the contents of the oven will be seen clearly. The oven is provided with an oil-tank K, which is connected by piping K² to the carbureter L and burners B. Surrounding my oven on three sides are flues M M. Also the top of the oven has passing over it flues N N. By this arrangement of flues a thorough and constant heat can be maintained in my oven. Above my burners I have provided plates O, which are placed at an angle to prevent the collection of soot in the corners of my casing surrounding the oven. The light I, placed in front of the glass window of the oven is provided with gas from the carbureter L through the pipe K⁵. The pipe K⁶ is provided for draining any residue of oil that might accumulate at the burner.

Having described my invention, what I claim, and desire to secure by Letters Patent of the United States, is—

The combination in an oil-heated oven of oil-burners located at the bottom and upper front of the oven, heating-flues on the three sides and top of the oven, windows in opposite sides of the oven, a light in front of one window, one of the sides of said oven being removable and shelving attached to said side to be removed therewith, substantially as described.

CHARLES HENRY HIGGINS.
